(71) Applicant: **Apple Inc.**, Cupertino, CA (US)

(72) Inventors: **Pablo Caro**, San Francisco, CA (US); **Jae Woo Chang**, Cupertino, CA (US); **Robert Garcia, III**, San Francisco, CA (US); **Marcel van Os**, Santa Cruz, CA (US)

(73) Assignee: **Apple Inc.**, Cupertino, CA (US)

(**) Term: **15 Years**

(21) Appl. No.: **29/851,334**

(22) Filed: **Aug. 26, 2022**

Related U.S. Application Data

(63) Continuation of application No. 29/726,320, filed on Mar. 2, 2020, now Pat. No. Des. 962,269, which is a continuation of application No. 29/650,076, filed on Jun. 4, 2018, now Pat. No. Des. 877,175.
